his Atty.

UNITED STATES PATENT OFFICE

FRIEDRICH GRIESER, OF BERLIN, GERMANY

HAIR TREATING DEVICE

Application filed March 8, 1929. Serial No. 345,288.

This invention relates to hair treating devices, and more particularly to devices of this kind which are designed to produce permanent hair-curls. The hair treating device according to my invention, more particularly, is so constructed that any heating by means of electric current or gas will entirely be dispensed with. For this purpose my new device comprises a heating body which is designed to act as a heat storage in such a way that the heat which emanates from said heating body will decrease simultaneously with the decrease of moisture contained in the hair, said decrease of moisture being due to the progress of the drying operation.

In the accompanying drawings I have represented an example of the hair treating or curling device constructed according to my invention, Fig. 1 being a longitudinal section through the new device in operative condition, Fig. 2 a section along line I—I of Fig. 1, Fig. 3 a detail view of the clamping device which serves for properly gripping a lock of hair to be treated, Fig. 4 a section along the line IV—IV of Fig. 1, Fig. 5 a diagrammatical section through the new hair treating device when applied to the head of a person, and Fig. 6 a detail representation of a specific cooling device which may be applied intermediate the head of a person and the hair treating device.

Referring now more particularly to the drawings, the hair treating device in its preferred construction consists of the following parts. The base-plate or bottom which consists of two parts *a* and *b* of oblong rectangular conformation is constructed to form a clamping device for gripping a lock of hair to be treated by the new device. The two parts *a* and *b* of said base-plate or clamping device may consist essentially of fibrous material and a cover or coating of metal may be applied to the upper surfaces thereof. The two parts or plates *a* and *b* of which the clamping device is composed are united with each other at one end by means of a hinge *f* having fixed points *e* and *e*, while at the other end of one of said plates *a* and *b* there may be provided a hook-shaped locking member *c* which engages with a pin *d* on the other

of said plates, as shown, for instance, in Fig. 3 of the drawings. Each of the outer edges of said plates *a* and *b* is provided with a resilient gripping member *g* and *g*, preferably of the form of leaf-springs, as may particularly be seen from Figs. 2 and 5, said gripping members serving for fixing the semi-cylindrical heating body *k* on the plates *a* and *b*. For this purpose the heating body *k* is provided with proper notches which may engage with said gripping members *g* and *g*, in the manner indicated in Figs. 2 and 5. As soon as the gripping members *g* and *g* engage with said notches in said heating body *k*, the latter will be properly kept in operative position on the plates *a* and *b*. It may be noted that the heating body *k* may be of a form different from that shown in the drawings, the form as shown, however, being preferable for various reasons. The shaft *p* provided on the heating body *k* is preferably surrounded by a sleeve *q* which consists of a heat insulating material. The handle may be separated from said shaft *p* and said sleeve *q* by interposing a washer *r* of metal or another substance. Mounted on the clamping device which is composed of the two parts *a* and *b* is a curling roller *h* which is equipped on both of its ends with cylindrical extensions *h*₁ and *h*₂. These extensions are roughened on their periphery for the purpose of preventing rotation of the curling roller during the process of curling. The outer ends of said cylindrical extension *h*₁ and *h*₂ carry discs *s*₁ and *s*₂, which discs may be provided with slots *t*₁ and *t*₂ serving for the reception of a screw driver or similar implement. Resilient bearing members *i*₁ and *i*₂ serve for firmly mounting said cylindrical extensions *h*₁ and *h*₂ and therewith the curling roller *h*. In this way the curling roller *h* will rest securely on the clamping device which is composed of the two plates *a* and *b*. The bearing members *i*₁ and *i*₂ are protected against being laterally tilted by said discs *s*₁ and *s*₂ on the one hand and by the enlarged ends of the curling roller *h* on the other hand.

The mode of operation of the hair treating device described in the foregoing will be as follows:

The lock of hair to be treated by the device is placed intermediate the two members *a* and *b* of the clamping device and firmly gripped thereby when closing said members *a* and *b* and locking the same by means of the locking member *c*. At the same time there will be provided a flat bottom or supporting surface for said semi-cylindrical heating body, said bottom or supporting surface having a metal coating. The lock of hair to be treated by the curling device is now wound upon the curling roller *h*, the curls produced by this device being essentially of the form of rolled curls, in contra-distinction to spiral-shaped curls. After placing a lock of hair *n* on said curling roller *h*, the latter is mounted upon the plates *a* and *b* of which the clamping device is composed. In order to properly protect the lock of hair *n* which is thus wound upon the curling roller *h*, preferably a sheet of asbestos and in addition to this a further covering of parchment *m* is interposed between said lock of hair and the heating body *k*. In order to draw tight the lock of hair, which is rolled up on the curling roller *h*, the discs *s*₁ or *s*₂ may be properly rotated by applying a screw driver to the groove or slot *t*₁ which as above mentioned is provided therein.

When using the present hair treating device the hair may be moistened or chemically treated in the heretofore usual way which of course does not form part of my present invention. Both bearing members *i*₁ and *i*₂ are now applied to the curling roller *h* which is placed upon the plates *a* and *b* which form the clamping device and thereupon the heating body *k* is placed upon said plates intermediate the gripping members *g* and *g*₁ until the latter will come into proper engagement with said heating body by means of the notches provided thereon. It is evident that in operative condition of my new hair treating device the semi-cylindrical heating body together with the two plates *a* and *b* of the clamping device will form an essentially closed space which is fully lined with metal. The curling roller *h* may likewise be made of metal.

Although the plates *a* and *b* which form part of the clamping device for the hair to be treated will ordinarily offer sufficient protection against the heat which emanates from the heating body *k*, it may be advisable to use an additional protection in the form of a cooling device, preferably of the form of a hose *o*, intermediate said plates and the head of the person whose hair shall be treated by the curling device.

The small thickness of the plates *a* and *b* and the provision of said additional protection will permit the hair treating device, as a whole, to easily fit the head of a person.

The interior portion of the hose *o* is provided

with a series of apertures, through which air coming from the container *u* may discharge, said container *u* being constantly supplied with fresh air, for instance by means of a fan or ventilator.

Experience has shown, that the application of electricity or gas for the purpose of steaming, drying or otherwise treating hair results in quite an amount of danger for the person to be treated. This danger is connected on the one hand with the nature of the source of heat and will therefore be inevitable, while on the other hand it resides in the mode of supplying heat to the hair, which mode is contradictory to the character of the steaming and drying process for living hair. Heretofore a gradual increase of heat had been produced in the hair to be treated, when employing heat generated by electrical resistances or by gas, and in addition to this an increasing amount of heat had been supplied to the hair during progress of the treatment.

For the purpose of boiling the hair, such as is necessary in order to produce durable curls, it will be necessary to apply the greatest amount of heat at the start and to continue the treatment with a gradually decreasing amount of heat. Only in this way it will be possible to safely prevent an excessive drying, singeing or roasting of the hair in a very simple manner. In addition, it has been found that with the new hair treating device which forms part of this invention the time required for the drying process may be reduced to one fifth of the time heretofore required for this purpose.

The new hair treating device according to my invention permits of being applied in a very simple and expeditious manner and in addition to this its mode of operation will be greatly simplified as compared with known devices of this kind. My new hair treating device furthermore may be exactly adjusted with respect to the thickness of the lock of hair to be treated at a time. In consequence of this it will be possible to carry out the treatment of the hair within a relatively very large range of temperature, in order to be able to properly adjust the temperature for various purposes. Even in case of treating thick and very moist locks of hair, which must be done at temperatures of 200° C. and more, no injuries to the skin will result, when using my new device. As a matter of fact, a person treated by my new device will hardly take notice of the fact that high temperatures are applied. On the other hand, when treating very thin locks of hair, by my present device, an excessive heating, burning or roasting of the hair will be safely prevented.

I claim:

In a hair treating device, the combination of a semi-cylindrical or essentially semi-cylindrical heating body, a bottom for said heating body, said bottom consisting of a

clamping device adapted to grip a lock of hair to be treated, a curling roller for said lock of hair, said curling roller being mounted within the space intermediate said heating body and said bottom, cylindrical roughened extensions on said curling roller, and resilient bearing members for said roughened extensions, said bearing members being adapted to prevent rotation of said curling roller and longitudinal displacement of said heating body during operation of said hair the curling device.

In testimony whereof I affix my signature.
FRIEDRICH GRIESER.
